UNITED STATES PATENT OFFICE.

WILLIAM F. SCHMIDT, OF RIDGEWOOD, NEW JERSEY.

METHOD OF FILING UNITS OF INTELLIGENCE.

1,305,939.

Specification of Letters Patent. Patented June 3, 1919.

Original application filed May 1, 1916, Serial No. 94,659. Divided and this application filed June 18, 1917. Serial No. 175,269.

To all whom it may concern:

Be it known that I, WILLIAM F. SCHMIDT, a citizen of the United States, and a resident of Ridgewood, Bergen county, State of New Jersey, have invented certain new and useful Improvements in Methods of Filing Units of Intelligence, of which the following is a specification.

This invention relates to improvements in methods of filing units of intelligence, and is a division of my co-pending application Serial No. 94,659, filed May 1st, 1916.

By the use of this invention, the methods of filing units of intelligence are greatly simplified, elaborate indexing and the use of confusing subcombinations of alphabetic characters are eliminated; great latitude for expansion or contraction is made possible and the manifold advantages of a numeric system without the elaborate indexing is procured.

In accordance with this invention, units of intelligence to be filed are first grouped in accordance with the alphabetic character thereof into main divisions, each of such main divisions are then identified with a distinguishing symbol, which preferably comprises one of the primary or secondary colors, and then each of the units of intelligence to be filed is again independently designated by a number in accordance with its alphabetic character so that a numeric subdivision of one of said colored main divisions is formed and the unit of intelligence is then filed away in the said numeric subdivision of the said colored main division.

In accordance with my preferred method individual and isolated alphabetic letters are so identified with a series of numbers, and preferably the digits, as to permit each of the said numbers to be identified with an isolated alphabetic character and also to permit interchangeable combinations of said numbers to be identified with interchangeable combinations of said letters. In order so to identify such alphabetic characters effectively with, for example, a series of digits, I preferably arrange a predetermined series of numeric characters, preferably 50 digits, into a plurality of horizontal and vertical intersecting columns, divide the alphabet, identify each of such alphabetic divisions with both a vertical column and a horizontal column of such numeric characters, and designate a unit of intelligence from the key so formed according to the

alphabetic combination of its filing title with a numeric combination comprising one of said series of numeric characters and a combination therewith of other numeric characters in the same series.

A filing clerk will, therefore, be enabled with great rapidity to place definitely in a properly designated subdivision of the main division any given unit of intelligence. Furthermore, such unit of intelligence will, because of its definite location, the rapidity with which the alphabetic combination of such unit may be translated by the use of the key into the numeric combination, and the well known ease and rapidity with which a sequential numeric system may be handled and referred to, always be readily and quickly available. Furthermore, because of the large number of subdivisions which are available though not necessarily employed, the unit of intelligence may be filed with substantial finality and the increase or decrease of the number of units of intelligence or in the amount of filing matter will not affect the sequential location of the filed units or matter.

I will now describe an outfit and key arranged for practising my invention.

In the accompanying drawings in which similar reference characters designate corresponding parts throughout the several views,

Figure 1 is a perspective view of a filing cabinet in which the drawers of the cabinet are made to form main divisions of my system, and are accordingly designated by colors;

Fig. 2 is a perspective view of a subdivision or folder adapted to be inserted in the red division;

Fig. 3 is a perspective view of another subdivision or folder adapted to be inserted in the yellow main division; and

Fig. 4 is a chart containing respectively my novel color classification key and my number assignment key employed in my filing system.

Referring now to these drawings which illustrate a preferred outfit for practising my invention, A indicates a filing cabinet which, as shown, is divided into eight main divisions or drawers which in accordance with my filing system are each marked with a distinguishing color preferably in the following sequential order: The drawer 1 is marked with the primary color "red," the

drawer 2 with the primary color "yellow," the drawer 3 with the primary color "blue," the drawer 4 with the secondary color "orange," the drawer 5 with the secondary color "green," the drawer 6 with the secondary color "purple," the drawer 7 with the basic color "white" and the drawer 8 with the color "black." These color designations with the exception of the color 10 "black," which is preferably reserved for confidential communications, are, by means of a color-classification key shown at the top of the chart in Fig. 4, identified with the alphabet, so that a unit of intelligence to be 15 grouped or classified may, through its alphabetical character, be instantaneously classified as belonging to a predetermined group.

It will be obvious that the prismatic colors 20 used will be readily discernible and distinguishable by an operator at a greater distance than would for instance alphabetic designations, and furthermore the elimination of such alphabetic designations for the 25 main divisions of the file will not only tend to greatly simplify the designations of the main divisions but when such color designations are used in combination with the numeric designations hereinafter referred to 30 will permit a great reduction of the main divisions of the system.

In identifying such colors with the alphabet I preferably divide the alphabet into sections, each beginning with a vowel or a semi-vowel, and one of said colors is assigned to 35 each of these alphabetic sections. By so subdividing the alphabet, I provide an aid to memory and also produce an initial distribution of great uniformity.

40 The main divisions so designated as aforesaid are subdivided preferably into numeric subdivisions each of which, as illustrated herein, preferably comprises a folder such as illustrated by the numerals 9 and 10 respectively, (Figs. 3 and 4). Each of these subdividing folders is preferably provided with a color designation corresponding to the color of the main division or group in which it is adapted to be employed or inserted. For example, the folder 9 (Fig. 3) 45 has printed thereon in red an oblong symbol 11 and the folder 10 has printed thereon in yellow a similar symbol 12. The folders so marked or designated are preferably furnished to the user in sets and it will be obvious that a set of such folders will be useful independently of the compartments comprising aforesaid main divisions and may be employed as a temporary color-classification outfit. Furthermore, a folder so designated 50 will, when removed from its place in a drawer, irrevocably retain its group classification as well as its numeric designation the derivation of which will now be described.

When a folder is to be employed as a subdivision, it is, independently of its color classification, given a numeric designation by means of the number-assignment key shown in Fig. 4, in which key each of the 70 digits or numbers 1 to 10 are identified with one or more isolated alphabetic letters as distinguished from identifying a digit or number with a group of such letters. Preferably the digits are in squared relationship 75 to and identified with the alphabet. In this key as illustrated the seven vowels and semi-vowels are omitted for the purpose of providing compactness, reducing the size of and simplifying the key and also to so reduce 80 the number of letters as to make the same divisible by the total number of digits, to wit: ten. The aforesaid omissions leave remaining nineteen consonants which with the character "&" makes twenty characters 85 which when divided in half and placed in double rows, as illustrated in said number assignment key, may be columned and alined evenly in squared relationship with said digits 0 to 9 inclusive. By placing the digits 90 in such squared relationship to the consonants, as illustrated in the said key in said Fig. 4, I am enabled to permit a digit and all possible and interchangeable numeric combinations of the other digits therewith 95 to be readily assigned to and identified with one or more isolated consonants or alphabetic characters in the key and such combinations with said character as will be found in a filing title, and I may allow the 100 omitted vowels and semi-vowels to be given the designation "0". The vowels and semi-vowels may be so designated without any confusion whatsoever and the doubling up of two consonants may be accomplished 105 without any repetition and confusion whatsoever because of the isolation of the characters so doubled, the previous splitting up into groups of such alphabetic characters and the identification of a color with each 110 group. Thus, while the characters B and N, for example, are placed in precisely the same relationship with the digits, the main or colored divisions of such characters will be different and therefore will be readily distinguishable. This double identification, therefore, of the isolated alphabetic characters first with a color symbol and then with a number permits without confusion the use of similar numerals in differently colored 115 main divisions and consequently increases the number of times the same numerals may be employed. Notwithstanding the compactness and simplicity of the key illustrated, it provides a great increase over 120 other systems in the possible number of subdivisions and gives great latitude and possibilities of expansion and contraction, while maintaining its numeric sequence. It will be apparent, therefore, that the filing clerk 125 130

will be enabled with great rapidity to place definitely in a subdivision having its proper numeric and color designations any given unit of intelligence and that the units of intelligence in any such subdivision as they multiply therein may be arranged alphabetically. Furthermore, any such unit of intelligence will, because of its definite location, the rapidity with which the alphabetic combination of such unit may be translated into the numeric combination, and in view of the well known ease and rapidity with which a sequential numeric system may be handled and referred to, always be readily and quickly available.

The omission of the vowels and semi-vowels and the arrangement of the consonants as illustrated, together with their alinement with the squared digits, will provide an aid to memory in case of the loss of the chart because in the color key the vowels split the alphabet into sections while in the numeric key the vowels are omitted.

The operation of my filing system applied to a system in which three-letter combinations are employed is as follows:

The grouping of the units into main divisions is accomplished by taking the first letter of the heading, title or subject of the unit of intelligence, consulting the color-classification key and designating either mentally or by writing the color division in which such letter is found. Thus in "Automobiles" the first letter being "A" is found in the red division and "Reports", the first letter being "R" will be found in the orange division. Now, for the purpose of placing the word "Automobile" in its numerically-designated subdivision, we take the first three letters "Aut" thereof and, consulting the number-assignment key, we find that the letters "a" and "u" being vowels will give us two ciphers, "00"; there is therefore but one letter to designate with a numeral. Consulting the alphabetic letters extending horizontally we find that directly beneath "t" in the first horizontal row of figures is the numeral 6 so that the numeric designation of the subdivision will be 006. Thus the title, heading or subject "Automobile" will be filed in subdivision "006" of the red main division. Taking the word "Reports", the first three letters being "Rep" the numeral "4" will be found in the first horizontal row under R and this will give as the first numeral of the designation the number "4", the next letter "e" being a vowel gives a cipher and we have the partial designation "40"; for the designation of the next consonant "p" we consult the letters extending vertically and take that one of the series of numerals placed in horizontal alinement with the letter p which is in the same vertical column or in vertical alinement with the initial letter. Thus the numeral which is in

horizontal alinement with "p" and in vertical alinement with r is "5" and we get "405" as the numeric designation. The item "Reports" will, therefore, be filed in folder 405 in the red division or drawer. 70 Taking the examples given on the chart as instructions, Cat will likewise be found to be folder 207 in the red drawer while R-Cl will be found to be 452, the third numeral being in the same vertical column as the first two 75 but in horizontal alinement with the letter "1". Similarly A M A representing American Manufacturing and Selling Co. will have the designation 000 in the red drawer.

Having described my invention, I claim: 80

1. The method of filing units of intelligence which comprises first the grouping of such units in accordance with the alphabetic character thereof into main divisions and assigning a distinguishable symbol to each of 85 such main divisions and then independently identifying isolated alphabetic characters of said unit with numbers and filing the unit of intelligence in accordance with said symbolic and numeric designations. 90

2. The method of filing units of intelligence which comprises first the grouping of such units in accordance with the alphabetic character thereof into main divisions, the assigning to each of such main divisions of a 95 color and the independent designation of the unit of intelligence by number in accordance with its alphabetic character to form a numeric subdivision of said colored main division and the filing away of the 100 unit of intelligence in said numeric subdivision.

3. The steps in the method of filing units of intelligence comprising the identifying of the individual alphabetic letters with a 105 series of numbers and the translating of the various interchangeable combinations of the alphabetic letters of the filing title of the unit of intelligence into similar interchangeable combinations of the individual numbers 110 of said series, and filing the unit accordingly.

4. The method of filing units of intelligence which comprises the grouping of such units of intelligence into main divisions and assigning to each such main division of a 115 distinguishable symbol, then independently identifying the individual letters of the alphabet with a series of digits and the translating of the various compound and complex combinations of the alphabetic letters of the filing title of the unit of intelligence into similar compound and complex combinations of the individual digits of said series, and filing the unit accordingly. 120

5. The step in the method of filing units of intelligence comprising the arranging of a predetermined series of numeric characters into a plurality of horizontal and vertical intersecting columns, dividing the alphabet, 130

identifying each of such alphabetic divisions with both a vertical column and a horizontal column of numeric characters, and designating a unit of intelligence from the key so formed according to the alphabetic combination of its filing title with a numeric combination comprising one of said series of numeric characters and a combination therewith of other numeric characters in the same series.

6. The method of filing units of intelligence comprising the dividing of a system into main alphabetic divisions, the assigning to each of such main divisions of a symbol, the arranging of a predetermined series of digits into a plurality of horizontal and vertical intersecting columns, dividing the al-

phabet into sets of characters, identifying each of such sets of alphabetic characters with a vertical column and also with a horizontal column of numeric digits and designating a unit of intelligence from the key so formed according to the alphabetical combination of its filing title with a numeric combination comprising one of said series of digits and the combination therewith of other digits in the same series.

In witness whereof, I have signed my name to the foregoing specification in the presence of two subscribing witnesses.

WILLIAM F. SCHMIDT.
